UNITED STATES PATENT OFFICE

159,316

BASEBALL SCORER

William Beach, Wilmington, Calif.

Application April 2, 1948, Serial No. 145,490

Term of patent 7 years

(Cl. D34—5)

To all whom it may concern:

Be it known that I, William Beach, a citizen of the United States, residing at Wilmington, in the county of Los Angeles and State of California, have invented a new, original, and ornamental Design for a Baseball Scorer, of which the following is a specification, reference being had to the accompanying drawing, forming part thereof, wherein:

Fig. 1 is a top plan view of the baseball scorer, showing my new design;

Fig. 2 is a side elevational view thereof,

Fig. 3 is an end elevational view thereof, the opposite end view being a mirror image of Fig. 3; and

Fig. 4 is a side elevational view thereof.

The back of the baseball scorer is plain and unornamented.

The dominant features of my new design are shown in solid lines in the drawing.

I claim:

The ornamental design for a baseball scorer, substantially as shown and described.

WILLIAM BEACH.
